UNITED STATES PATENT OFFICE.

WILLIS C. ARNOLD, OF WARSAW, NEW YORK, AND WILLIAM E. DATE, OF WESTFIELD, NEW JERSEY, ASSIGNEES TO THE CUTLER-HAMMER MFG. CO., OF MILWAUKEE, WISCONSIN, A CORPORATION OF WISCONSIN.

ELEVATOR-CONTROLLER.

1,262,617.

Specification of Letters Patent. Patented Apr. 16, 1918.

Application filed February 28, 1916. Serial No. 80,934.

To all whom it may concern:

Be it known that we, WILLIS C. ARNOLD and WILLIAM E. DATE, both citizens of the United States, residing, respectively, at 5 Warsaw, in the county of Wyoming and State of New York, and Westfield, in the county of Union and State of New Jersey, have invented new and useful Improvements 10 in Elevator-Controllers, of which the following is a full, clear, concise, and exact description, reference being had to the accompanying drawing, forming a part of this specification.

This invention relates to improvements in 15 elevator controllers and more particularly to door control means for push button elevator systems.

One of the objects of the invention is to provide simplified and thoroughly reliable 20 door controlling means which will insure against the opening of any landing door during travel of the elevator car and which will further automatically release the door at the landing to which the car is brought to 25 rest.

A further object is to provide purely mechanical means for the aforesaid purposes thereby avoiding further complication of the necessarily elaborate electrical systems required 30 for elevators of this class and further rendering the action of said means entirely independent of any electrical disorders in the control system employed.

Other objects and advantages will herein- 35 after appear.

The accompanying drawing illustrates schematically one embodiment of the invention which will now be described, it, of course, being understood that the invention 40 is susceptible of embodiment in other forms.

Referring to the drawing there is schematically illustrated therein an elevator car 1, traveling in a hatchway 2 shown as provided with landings 3, 4 and 5 having doors 45 3^a, 4^a and 5^a respectively. Each door is schematically illustrated as provided with a locking mechanism 6 and each of said mechanisms is shown as provided with a tripping

member 7 extending into the hatchway and carrying at its extremity an anti-friction 50 roller 8. Normally the locking mechanisms lock their respective doors in closed position and release of each door requires movement of its lock tripping member 7 to the left.

The release of the doors is accomplished 55 by the following means. A so-called retiring cam 9 is pivotally mounted on the car 10 and is biased by suitable means, such as a spring 11, into a position to engage and press to the left the tripping member of each 60 door locking mechanism in passing the same. The retiring cam 9, however, is provided with a link 12 passing through a bracket 13 and having an offset roller 14 to engage cams arranged in the hatchway for the purpose of 65 withdrawing said retiring cam from operative relation with the lock tripping members. The hatchway cams comprise three sets 15, 16 and 17, one set for each landing and all fixed to the usual car guide 18. 70 Each set of hatchway cams includes two cams *a* and *b* so formed as to both draw the retiring cam 9 to the left and so arranged as to release the link 12 therebetween when the car is directly opposite the respective landing. 75 Accordingly as the car approaches each landing in ascending the corresponding cam *a* will act to deflect the retiring cam 9 while as the car approaches each landing in descending the corresponding cam *b* serves 80 the same purpose. However, as the car directly registers with each landing the retiring lever is released and its spring 11 tends to immediately throw the same against the corresponding lock tripping member to 85 release the respective door. Thus the retiring cam is given a time element in its lock tripping action and a dash-pot 19 is connected to said cam to further delay its return tripping movement.

Thus it will be readily apparent that by proper adjustment of the dash-pot the retiring cam may be so timed in its tripping operation as to require arrest of the car at a given landing to render the same effective to 95 release the door of such landing. Or, in

other words, it may be rendered so sluggish in its operation that unless the car is halted in its travel upon reaching a landing the link of the retiring cam will successively engage both hatchway cams corresponding to said landing with such rapidity as to prevent action of said retiring cam to release the door of such landing.

Hence if a car is called to a particular landing all doors will be maintained locked until the car reaches and stops at said landing and "stealing" of the car by opening of the door of some other landing will be positively precluded. Moreover, it will be observed that the aforesaid operation of the locking and tripping mechanism is in no wise dependent upon or affected by the electrical system utilized for control of the car.

What I claim as new and desire to secure by Letters Patent is:

1. In a control mechanism for elevator landing doors, the combination with a landing door lock, of means tending to trip said lock upon landing positioning of the elevator and self controlled means acting upon through operation of the elevator to prevent tripping action of the former means.

2. In a control mechanism for elevator landing doors, the combination with a landing door lock, of a mechanical device tending to trip said lock upon landing positioning of the elevator and self controlled means functionally operable by power derived from the elevator to prevent tripping action of the former means except upon arrest of the elevator in landing position.

3. In a control mechanism for the landing doors of an elevator, the combination with a landing door lock, of means tending to trip said lock automatically upon landing positioning of the elevator, said means being ineffective in all other positions of the elevator and including means providing a time element in the tripping action thereof whereby it is rendered ineffective for tripping of said lock except upon arrest of the elevator.

4. In a control mechanism for the landing doors of an elevator, the combination with a lock for each door, of mechanical means for tripping said locks automatically upon positioning of the elevator at landings corresponding to said locks, said means being effective only in landing positions of the elevator and including means providing a time element in the tripping action thereof whereby it is rendered ineffective for tripping said locks except upon arrest of the elevator.

5. In a control mechanism for elevator landing doors, the combination with a lock for each door, of a mechanical tripping device for said locks movable with the elevator and self controlled means acting upon said device during approach of the elevator to each landing to render said device temporarily ineffective, for the purpose set forth.

6. In a control mechanism for elevator landing doors, the combination with a lock for each door, of a mechanical tripping device for said locks movable with the elevator and tending to assume a tripping position, and displacing means for said device whereby the latter is temporarily withdrawn from tripping position upon approach of the elevator to each landing and by power derived from the elevator.

7. In a control mechanism for the landing doors of an elevator, the combination with a lock for each door, of a mechanical device movable with the elevator and including a movable part tending to trip said locks automatically upon positioning of the elevator at their corresponding landings, means for displacing said movable part from tripping position upon approach of said elevator to each landing and means for retarding return of said part to tripping position to thereby necessitate arrest of the elevator for tripping action thereof.

8. In a control mechanism for the landing doors of an elevator, in combination, a locking device for each door, each of said devices having a tripping part, a device movable with the elevator to actuate said tripping part of said locking devices, said actuating device being biased in a direction distinct from its direction of travel and being ineffective when displaced against its bias and means acting upon the approach of the elevator to each landing to displace said actuating device and release the same in landing position of the elevator.

9. In a control mechanism for the landing doors of an elevator, in combination, a locking device for each door, each of said devices having a tripping part, a device movable with the elevator to actuate said tripping part of said locking devices, said actuating device being biased in a direction distinct from its direction of travel and being ineffective when displaced against its bias, means opposing biased movement of said actuating device to insure a delayed return thereof, and means acting upon the approach of the elevator to each landing to displace said actuating device and release the same in landing position of the elevator.

10. In a control mechanism for the landing doors of an elevator, the combination with a lock for each door, a pivoted member movable with the elevator and biased toward a position whereby the same tends to trip said locks automatically upon positioning of the elevator at their correspond-

ing landings, a plurality of stationary cams located at each landing for displacing said member from tripping position during approach of the elevator into each landing position and for releasing the same in landing position of the elevator and a dash pot for retarding return of said member upon dis-

placement thereof whereby the same is rendered ineffective to trip said locks except upon arrest of the elevator. 10

In witness whereof, we have each hereunto subscribed our names.

WILLIS C. ARNOLD.

WILLIAM E. DATE.
